STEAM JET REFRIGERATION APPARATUS

Paul L. Fetzer, Ridley Park, Pa., assignor to Westinghouse Electric & Manufacturing Company, East Pittsburgh, Pa., a corporation of Pennsylvania

Application March 2, 1933, Serial No. 659,403

4 Claims. (Cl. 62—152)

My invention relates to refrigerating apparatus, more particularly to apparatus of the type known as steam jet refrigerating apparatus, and it has for an object to provide improved apparatus of this type which is adapted for operation at partial load.

Apparatus of this type includes a chamber in which a vacuous or reduced pressure condition is maintained by an ejector or compressor, exhausting usually to a condenser. Liquid to be cooled, usually water, is circulated or conveyed through the chamber, the reduced pressure therein effecting evaporation of a portion of the liquid and consequent cooling of the remaining liquid, which then provides the supply of refrigerated liquid and which may be used as refrigerating medium. A steam ejector is not always sufficiently adaptable to change in load, and is usually operated at full load, that is, with full admission of motivating steam or other fluid.

In order to provide economy of operation at partial load, it has been proposed to provide a plurality of ejectors in parallel and to operate only some of them at partial load. It is necessary with this arrangement, however, to provide a shut-off valve for each ejector which may be shut off at partial load, in order to prevent reverse flow therethrough from the condenser to the evaporating chamber, which would destroy the vacuous condition therein. Due to the large size of the vapor connection, such a valve and its operating mechanism represents a considerable item of expense. Such a valve has other objections, such as air leakage into the vacuum system.

It is a particular object of my invention to provide apparatus in which said valve is not required.

In accordance with my invention, I provide a plurality of evaporating chambers or compartments into which liquid to be cooled is admitted. A separate ejector is provided for each chamber and a common condenser is provided for the ejectors. I provide conduit means for removing cooled liquid from the chambers, and I arrange the conduit means with a manometric connection or loop seal between the chambers, the manometric connection providing a column of liquid whose pressure head opposes the increased pressure, during partial load operating, in that chamber whose ejector is shut down.

The above and other objects are effected by my invention as will be apparent from the following description and claims taken in accord-

ance with the accompanying drawings, forming a part of this application, in which:

Fig. 1 is a diagrammatic elevation view of the refrigerating apparatus; and,

Fig. 2 is a plan view of the apparatus showing the ejectors and the common condenser.

Referring now to the drawings more in detail, I show steam jet refrigerating apparatus for supplying cooled liquid, such as water, to any apparatus in which it may be required. Such apparatus may be, for example, the air cooler and washer of air conditioning apparatus, shown on the drawings at 9.

The refrigerating apparatus comprises a primary evaporating chamber 10 and a secondary evaporating chamber 11. In the present embodiment, these chambers are formed by separate tanks. Steam ejectors 12 and 13, shown in Fig. 2, have their suction inlets 12' and 13' connected to the chambers 10 and 11, respectively, and effect a vacuous or reduced pressure condition in the respective chambers by withdrawing vapor therefrom. The ejectors 12 and 13 are motivated by steam from a supply conduit 14, the admission thereof being controlled by valves 15 and 16, respectively, the operation of which is described later. The ejectors exhaust into a common condenser 17, which is provided with a condensate outlet 18, and air outlet 19 connected to an air ejector 20, a cooling water inlet 21 and a cooling water outlet 22.

For full load operation, both ejectors are operated. For partial load operation, only the ejector 12 is operated, the ejector 13 being shut down by closing the valve 16. The condenser pressure is then admitted into the chamber 10 through the ejector 13.

The water to be cooled is conveyed, in this case from the air cooler, by a conduit 23 to the evaporating chamber or chambers. The water is divided, one portion being admitted always to spray nozzles 24 in the chamber 10. The remaining portion is admitted by a valve 25 either to a second group of spray nozzles 26 in the chamber 10, for partial load operation, or to spray nozzles 27 in the chamber 11, for full load operation. Upon being subjected to the vacuum or decreased pressure in the evaporating chamber, the water is partially evaporated, which action effects cooling of the remaining water, as is well known in the art.

The water cooled in each evaporating chamber is discharged therefrom through an outlet in the bottom, the bottom preferably converging toward the outlet. The outlets are connect-

ed to a system of conduits, which is, in accordance with the present invention, arranged to provide a manometric connection or loop seal between the chambers to seal the chamber 10 against the higher absolute pressure in the chamber 11 at partial load operation. This conduit system includes separate branch discharge conduits 28 and 29 communicating with the chambers 10 and 11, respectively, and with a common discharge conduit 31. The conduit 29 is of smaller diameter than the conduits 28 and 31, as it never conveys more than a portion of the water, while the conduit 28 conveys the full quantity of water at partial load. The conduits 28 and 29 extend first downwardly and then communicate at a low level through horizontally extending portions, thereby providing the manometric connection or loop seal between the chambers 10 and 11. The conduit 28 is of sufficient height to provide a head of liquid "a" which opposes the increase in pressure in the chamber 11 at partial load. The water is then conveyed by the conduit 31, to a pump 32, by which it is forced through a conduit 33 to the air cooler or other refrigerating load. In the latter, the cooled water is used as refrigerating medium for any desired purpose, such as air cooling. Its temperature having been increased, it is discharged from the air cooler to the conduit 23 and recirculated.

Control mechanism for regulating the operation of the refrigerating apparatus is provided. It includes solenoids 34 and 35 for opening valves 15 and 16, respectively, the latter being biased to closed position by the weight of the core. A solenoid 36 controls the valve 25, which is biased to the position in which it admits water to the nozzles 26 in the chamber 10, and is operated to admit water to the nozzles 27 in the chamber 11 when the solenoid 36 is energized. The solenoid 34 is controlled by contacts 37, and the solenoids 35 and 36 are controlled by contacts 38. The contacts 37 and 38 are controlled by a thermostat 39 in response to the temperature of the liquid to be cooled at any desired point in its circuit or path. Preferably, and as shown, the thermostat includes an expandible bellows 41 connected by a tube 42 to a bulb 43 disposed in the conduit 31. The thermostat 39 is arranged to close the contacts 37 in response to a predetermined maximum temperature, to close both contacts 37 and 38 in response to a slightly higher predetermined maximum temperature, and to open both contacts 37 and 38 in response to a temperature lower than the first-mentioned predetermined maximum temperature. For the purpose of an example, the first and second predetermined maximum temperatures will be taken as 40° and 41° F., respectively.

60 Make-up water to replace the water which is vaporized and removed is supplied through a conduit 44. It is preferably first cooled in one of the evaporating chambers, and hence the conduit 44 may be connected to the conduit 23. The admission of make-up water is controlled by a valve 45, which is controlled by a float control 46 in response to the level of water in the chamber 10.

The operation of the above-described apparatus is as follows:

70 When the air cooler or other refrigerating load requires the maximum amount of refrigeration, this is evidenced by a temperature of the circulating water of 41° F. or higher. The thermostat 39 closes contacts 37 and 38, rendering both

ejectors operative, and adjusting the valve 25 to admit water to the chamber 11. Approximately one-half of the water, or any other desired portion, is admitted to the chamber 11, and the remaining portion to the chamber 10. The water is cooled or refrigerated in the respective chambers as above described, substantially the same degree of vacuum or pressure being maintained therein. The water is discharged in parallel through the conduits 28 and 29 to the conduit 31, and supplied to the air cooler.

As the requirement for refrigeration decreases, the temperature of the water decreases. However, the contacts 38 will be kept closed and the apparatus maintained at full load operation until the temperature drops below 41° F., indicating that half load operation will supply the needed refrigeration, at least temporarily. The contacts 38 are then opened, deenergizing the solenoids 35 and 36. The ejector 13 is shut down and the valve 25 diverts the water from the chamber 11 to the chamber 10. Due to the shutting down of the ejector 13, the pressure in the chamber 11 will rise to that in the condenser 17, lowering the level of the water in the conduit 29, until the difference in head between the column of water in the conduit 28 and the bottom of the chamber 10 and the water in the conduit 29, indicated by the reference character "a", balances the difference between the absolute pressures in the two evaporating chambers. The full quantity of water then flows through the chamber 10, the branch discharge conduit 28 and the common conduit 31, while the water in the branch discharge conduit 29 remains stationary. It is to be noted that the higher pressure in the chamber 11 tends to heat the water, but as the level of the water is down in the conduit 29, the amount of surface of water subject to heating will be negligible.

40 If the refrigeration requirement is substantially less than full load, and greater than half load, there will be intermittent full load and half load operation, the temperature of the water decreasing during the full load operation and increasing during the half load operation.

If the temperature of the water drops below 40° F., indicating that no further refrigeration is presently needed, the contacts 37 are also opened, shutting down the ejector 12. The water is then circulated through the chamber 10 without any cooling except for the action of the air ejector 20 of the condenser, which effects a small amount of evaporation of the water and consequent cooling. Upon subsequent increase in temperature of the water, the contacts 37 will reclose, and cooling at half load is resumed. Thus, a load less than half load is taken care of by intermittent half-load operation.

60 From the above description, it will be seen that I have provided a liquid seal between the two evaporating chambers for partial load operation, thereby eliminating the necessity for a valve and its operating and control mechanism, which would otherwise be required to prevent the condenser pressure entering the chamber 10 through the ejector 13 and the chamber 11.

70 While I have shown my invention in one form, it will be obvious to those skilled in the art that it is not so limited, but is susceptible of various other changes and modifications without departing from the spirit thereof, and I desire, therefore, that only such limitations shall be placed thereupon as are imposed by the prior 75

art or as are specifically set forth in the appended claims.

What I claim is:

1. Refrigerating apparatus for providing a supply of cooled water comprising first and second evaporator chambers, means including a discharge conduit for effecting flow of water through said chambers to be cooled therein, for delivering the same to the discharge conduit and for providing a liquid seal between the chambers, first and second ejectors connected to said first and second chambers for withdrawing vapor therefrom, respectively, means responsive to increase above and decrease below a predetermined temperature of the water flowing through said discharge conduit for initiating and terminating operation of said first ejector and responsive to increase above and decrease below a slightly higher predetermined temperature of said water for initiating and terminating flow of water through the second chamber and operation of the second ejector.

2. Refrigerating apparatus comprising a plurality of evaporator chambers, means for conveying water through said chambers in parallel to be cooled therein by partial evaporation and including a common discharge conduit, an ejector associated with each chamber for withdrawing vapor therefrom, and means for initiating operation of an ejector of one chamber in response to a predetermined maximum temperature of the water flowing through said common discharge conduit and of an ejector of a second chamber in response to a slightly higher predetermined temperature thereof.

3. Refrigerating apparatus comprising a plu-

rality of evaporator chambers, means for conveying water through said chambers in parallel to be cooled therein by partial evaporation and including a common discharge conduit, an ejector associated with each chamber for withdrawing vapor therefrom, and means for automatically controlling the operation of the ejectors of a plurality of chambers in response to the temperature of the water flowing through said common discharge conduit to maintain said temperature substantially constant, said last-mentioned means operating in the direction to initiate operation of the ejectors in response to increase in said temperature and in the direction to terminate operation of the ejectors in response to decrease in said temperature.

4. Refrigerating apparatus comprising a plurality of evaporator chambers, means for conveying water through said chambers in parallel and including a common water supply conduit, a common discharge conduit, and branch conduits connecting the chambers with the common discharge conduit and arranged to form a liquid seal between the chambers, an ejector connected to each chamber for withdrawing vapor therefrom, and means for controlling the ejectors of a plurality of said chambers in response to the temperature of the water flowing through said common discharge conduit to maintain said temperature substantially constant, said last-mentioned means operating to initiate operation of each ejector controlled thereby in response to increase in said temperature and to terminate operation thereof in response to decrease in said temperature.

PAUL L. FETZER.
